CLAIM

The ornamental design for an exterior lighting fixture, as shown and described.

DESCRIPTION

FIG. 1 is a bottom, front perspective view of an exterior lighting fixture showing my new design, the post mount being shown in broken lines for illustrative purposes only and forming no part of the claimed design;

FIG. 2 is a front elevational view thereof;

FIG. 3 is a left side elevational view thereof, with the right side being a mirror image, and the lateral mount being shown in broken lines for illustrative purposes only and forming no part of the claimed design;

FIG. 4 is a rear elevational view thereof;

FIG. 5 is a top plan view thereof;

FIG. 6 is a bottom plan view thereof.

FIG. 1
